UNITED STATES PATENT OFFICE.

FREDERICK MARGGRAFF, OF AUGUSTA, KENTUCKY.

WIRE-BUTTON MACHINE.

No. 846,330.

Specification of Letters Patent.

Patented March 5, 1907.

Application filed July 29, 1904. Serial No. 218,621.

To all whom it may concern:

Be it known that I, FREDERICK MARGGRAFF, a citizen of the United States of America, and a resident of Augusta, county 5 of Bracken, State of Kentucky, have invented certain new and useful Improvements in Wire-Button Machines, of which the following is a specification.

The object of my invention is a machine 10 for forming wire buttons from a coil of wire which is fed into it in a rapid and efficient manner.

Referring to the accompanying drawings, in which like parts are indicated by similar 15 reference-letters wherever they occur throughout the various views, Figure 1 is a plan view of a wire-button machine embodying my invention. Fig. 2 is a detail sectional view taken upon line $x-x$ of Fig. 1. Fig. 3 is a sectional view taken upon line $y-y$ of Fig. 1. Fig. 4 is a detail front elevation 20 of the compressed jaws, showing them in the position they occupy while the wire is being carried between them to form it into a **U** shape. Fig. 5 is a similar view of the same 25 after the jaws have closed in upon the prongs. Fig. 6 is a detail plan view of the jaws after they have compressed the prongs together, the dotted line showing the position 30 of the parts just before the jaws are brought together. Fig. 7 is a similar view showing the position of the blank just before the upper bending-rod descends. Fig. 8 is a 35 sectional view showing the position of the parts after the upper bending-rod has descended. Fig. 9 is a detail perspective view 40 of the blank shown in Fig. 8. Fig. 10 is a similar view to Fig. 8, showing the lower bending-rod carrying the loop of the blank 45 upward. Fig. 11 is a view similar to Figs. 8 and 10, showing the ram for bending the loop at right angles to the prongs to form the back and to complete the blank. Fig. 12 is a perspective view of the completed blank 50 made by my machine. Fig. 13 is a detail plan view of the end of the bar for actuating the reciprocating finger, which operates the mechanism for gripping the wire.

Referring to the parts, the frame of my 55 machine has longitudinal arms A and transverse arms A', in which are cut longitudinal ways a and transverse ways a' . Mounted in ways a are compression-jaws B and B', which are reciprocated at intervals by cams b and b' , mounted upon rotating shafts b^2 and b^3 . Jaws B and B' have transverse horizontal grooves

b^4 b^5 cut into their meeting faces. Said jaws stand normally at a distance apart equal to the diameter of the head M of the blank, as shown in Fig. 4. Mounted in ways a' is a reciprocating bar C, which is moved in one direction by a cam c and returned in the other direction by a cam c' and a rod c^2 , both cams being mounted upon a rotating shaft c^3 , which has bevel-wheels c^4 c^5 , the latter of which meshes with a bevel-wheel upon the driving-shaft b^3 and the former of which meshes with a similar wheel upon shaft b^2 .

Carriage C has mounted upon it a cylindrical pin E, whose diameter is equal to that of the interior diameter of the head M. Fitted upon pin E is a gripping-jaw e, the upper end e' of which is adapted to coöperate with pin E to grip the wire m and the opposite end e^2 of which stands normally in the path of a reciprocating finger D, which is likewise carried by carriage C. Finger D is coupled by a link d to a bar D', which has a slot having a horizontal portion d' and an inclined portion d^2 . This slot engages pin e^3 upon the side of reciprocating pin E. Projecting downwardly from finger D is a stud a^3 , which fits into an inclined slot f in a reciprocating bar F, which is mounted to slide with carriage C and to be actuated by a cam b^6 upon the shaft b^3 , so as to have a longitudinal reciprocation, which causes finger D and bar D' to have a transverse motion relative to carriage C in addition to the motion of said carriage.

The operation of the parts thus far described are as follows: The wire m is fed across the front of the jaws B and B' at a height of the grooves b^4 b^5 by a wire-feed G and between the pin E and finger e' . The wire-feed and the wire-cutter g for severing the desired length of wire for making a button are of ordinary construction. When the wire comes between the pin E and the gripping-finger e' , the reciprocating finger D, carried forward by the reciprocation of the bar F, throws the arm e^2 down and causes the finger e' to hold the wire tightly against the pin E. Carriage C is then reciprocated by the cam c to carry the pin E with the wire m forward between the jaws B and B', while they are held a distance apart equal to the diameter of the head M. This bends the wire into the **U** shape shown in dotted line in Fig. 6, the ends lying in grooves b^4 b^5 . The jaws B and B' are brought together after the pin E has passed clear of them, and the wire

is bent about the pin E in the manner shown in Fig. 6, the grooves b^4 b^5 preventing the wires forming the prongs from overlapping. After the prongs have been pressed together, as shown in Fig. 6, about the pin, the cam c' causes the carriage C to have a forward movement given to it and causes the blank to be carried through and beyond the closed jaws, as shown in Fig. 7, a distance equal to one-half the diameter of the head M, so as to make allowance for radial bend m' in the prongs, as shown in Fig. 12. The reciprocation of the bar F then causes the finger D and the bar D' to be retracted, so that the finger D is out of contact with the arm e^2 , which draws the finger e' away from pin E to release the blank M therefrom, the retraction of the bar D' causing the inclined slot d^2 to lower the pin E below the jaws B and B', leaving the blank held therein. Then the cam retracts carriage C to carry it back and take a fresh piece of wire, leaving the blank held between the jaws B and B' in the position shown in Fig. 7. Carriage C halts upon its return movement to allow ram R to operate on the blank, as hereafter described.

The mechanism for bending the head at right angles to the prongs will now be described. Pivoted upon the side of the frame A are arms H H', the former of which carries at its inner end the upper bending-rod h and the latter of which carries at its end the lower bending-rod h' , the rods being arranged to stand normally one above, the other below, the ways a' at the rear of the jaws B and B' and at a distance apart such as to allow the pin E and the arm to pass between them. Arms H and H' are pivoted at their outer ends to arms h^2 h^3 , which at their other ends are pivoted together at h^4 and to a stud h^5 , projecting down from a reciprocating arm h^6 , which has a yoke to pass over shaft b^3 and a slot h^7 to engage a guide-pin a^2 , projecting out from the frame A. The arm h^6 has a pin h^8 , which engages a cam-slot b' in a rotating wheel b^8 , mounted upon shaft b^3 . The rotation of the wheel b^8 causes the arm h^6 to have a reciprocation, and therefore causes the arm h^5 to be carried back and forth, and thereby to turn the arms H H' upon their pivots to actuate the bending-rods h h' . After the blank has been fed forward to the position shown in Fig. 7 the rotation of the wheel b^8 causes the rod h to descend, its lower tapered end h^9 entering the loop M and bending the blank down to the position shown in Fig. 8, forming the part m' of the prongs. The camway b' then causes the rod h to be carried up out of contact with the blank at the same time that the rod h' is brought upward, its upper end engaging the loop M and bending it upward, as shown in Fig. 10. Then the reciprocation of the cam b^8 causes the arms H H' to be drawn apart, the return motion of the carriage C then causing the ram

R, which is mounted upon the carriage C, to be brought against the blank shown in Fig. 10 and to flatten the head firmly against the jaws B and B', bending the head at right angles to the prongs, as shown in Figs. 11 and 12. 7c

What I claim is—

1. In a machine for forming wire buttons the combination of movable compression-jaws, a pin for carrying wire forward between the jaws while they stand apart to bend it 75 into a U shape, means for carrying the pin forward between and stopping it just beyond the jaws, means for then moving the jaws together to bend the wire around the pin to form the head and prongs of the blank, and 80 means for bending the head relatively to the prongs while they are held between the compression-jaws.

2. In a machine for forming wire buttons the combination of movable compression-jaws having registering grooves upon their meeting faces, a pin for carrying a wire forward between the jaws and in the grooves, to bend it into a U shape, means for carrying the pin forward between and stopping it just 90 beyond the jaws, a means of moving the jaws together to bend the wire around the pin to form the head and prongs of the blank, and means for bending the head relatively to the prongs while they are held between the 95 jaws.

3. In a machine for forming a wire button the combination of movable compression-jaws, a means for feeding the wire forward between the jaws to form it into a U shape, 100 means for bringing the jaws together after the bend of the U has passed them to form a head projecting beyond and adjacently-disposed prongs held between the jaws, bending members adjacent to the jaws, a means for actuating one of said members to bend the prongs at a short distance from the head and means for actuating the other bending member to bend the head back upon the bent portion of the prongs. 105

4. In a machine for forming wire buttons the combination of movable compression-jaws, a pin for pushing a wire forward between the jaws, means for arresting the movement of the pin just beyond the jaws, a means 115 for bringing the jaws together to bend the wire around the pin to form the button-head, a means for disengaging the pin from the wire, bending members adjacent the jaws, and a means for actuating them to bend the 120 head relatively to the prongs.

5. In a wire-button machine the combination of movable compression-jaws, a carriage, a pin and a gripping-jaw mounted on the carriage, a finger mounted movably on the carriage, means for carrying the finger into contact with the gripping-jaw to cause it to hold a wire against the pin, a means for reciprocating the carriage to carry the pin forward between the compression-jaws, and a means 130

for bringing the jaws together to bend the wire about the pin to form the head.

6. In a wire-button machine the combination of movable compression-jaws, a carriage, a pin and a gripping-jaw mounted on the carriage, a finger mounted movably on the carriage, means for carrying the finger into contact with the gripping-jaw to cause it to hold a wire against the pin, a means for reciprocating the carriage to carry the pin forward between the compression-jaws, a means for bringing the jaws together to bend the wire about the pin to form the head, bending members for putting a double bend in the prongs adjacent to the head, and a ram for flattening the bend against the compression-jaws to form the head at right angles to the prongs.

7. In a wire-button machine the combination of movable compression-jaws, a carriage, a movable pin and a gripping-jaw mounted upon the carriage, a sliding finger and a sliding bar, means for actuating the finger and the bar to cause the former to contact said jaw for holding a wire thereto and the latter to withdraw the pin from contact with the wire, means for moving the carriage forward to carry the pin between the jaws, means for bringing the jaws together to bend the wire about the pin, bending members adjacent to the jaws and means for actuating them to bend the head relatively to the prongs after the pin has been withdrawn from the head.

8. In a wire-button machine the combination of movable compression-jaws, a carriage, a movable pin and a gripping-jaw mounted upon the carriage, a sliding finger and a sliding bar, means for actuating the finger and the bar to cause the former to contact said

jaw for holding the wire thereto and the latter to withdraw the pin from contact with the wire, means for moving the carriage forward to carry the pin between the jaws, means for bringing the jaws together to bend the wire about the pin, bending members mounted adjacent to the jaws, means for actuating them to put a double bend in the prongs adjacent to the head and a ram mounted upon the carriage to flatten the head against the compression-jaws to form the same at right angles to the prongs.

9. In a wire-button machine the combination of compression-jaws, means for feeding a wire across the jaws, a carriage, a movable pin mounted upon the carriage, means for actuating the carriage to carry the pin forward between the compression-jaws to push the wire between the jaws to form it into a **U** shape, means for bringing the compression-jaws together to bend the wire about the pin to form the head and to bring the prongs adjacent to each other, a means for giving a short additional step to the carriage to carry the head a short distance beyond the compression-jaws, means for withdrawing the pin from the head, bending members mounted adjacent to the jaws, means for actuating one to bend the prongs adjacent to the compression-jaws, a means for actuating the other bending member to bend the head at the end of the prongs, a ram mounted upon the carriage and a means for actuating the carriage to carry the ram against the button-head and the compression-jaws.
